BENJAMIN H. SMITH, OF TURTLE CREEK, AND PAUL MACGAHAN, OF PITTSBURGH, PENNSYLVANIA, ASSIGNORS TO WESTINGHOUSE ELECTRIC AND MANUFACTURING COMPANY, A CORPORATION OF PENNSYLVANIA.

ELECTRICAL PROTECTIVE DEVICE.

1,199,437.

Specification of Letters Patent. Patented Sept. 26, 1916.

Application filed November 5, 1913. Serial No. 799,266.

To all whom it may concern:

Be it known that we, BENJAMIN H. SMITH, a citizen of the United States, and a resident of Turtle Creek, in the county of Allegheny and State of Pennsylvania, and PAUL MACGAHAN, a citizen of the United States, and a resident of Pittsburgh, in the county of Allegheny and State of Pennsylvania, have invented a new and useful Improvement in 10 Electrical Protective Devices, of which the following is a specification.

Our invention relates to electrical protective devices and particularly to relays.

The object of our invention is to provide 15 a high tension relay having its contact members located an appreciable distance from its operating electromagnet.

High tension relays have heretofore been made in compact units with the contact and 20 adjusting members in close proximity to the operating electromagnet. This practice was considered dangerous and it did not permit of easy inspection and adjustment.

In our present invention, we provide a 25 relay which has its high-tension electromagnet so located as to eliminate the danger of any one coming into contact with it, and which has a contact device, a time element, and a load setting adjustment connected to 30 the high-tension electromagnet by a suitably insulated rod of appreciable length. The contact device may be located beneath or at either side of the electromagnet, and it may be adjusted for any time element 35 characteristic.

Our invention has the advantage of absolute safety from the high voltage and admits of increased accessibility for adjustment.

40 In the accompanying drawings Figure 1 is a view of a relay shown partially in elevation and partially in section wherein is embodied our invention; Fig. 2 is a fragmentary view of the relay shown in Fig. 1 arranged for horizontal connection and shown partially in elevation and partially in section; Fig. 3 is a side sectional view of a spring member which is used in one modification of our invention, and Fig. 4 is a 45 sectional view, taken along the line IV—IV of Fig. 1.

Referring particularly to Fig. 1 of the drawings, our invention comprises an electromagnet 1 having a winding 2, a movable

core 3, and a bell crank 4 that is pivoted 55 on a projection 5 on the case 6 of the electromagnet 1. The core 3 is pivotally attached to the arm 4^a of the bell crank 4 and its degree of downward movement is limited by that of the arm 4^a which is limited 60 by a rod 7 attached to the electromagnet case 6. A rod 8 constructed of insulating material connects the arm 4^a to a lever 9 that is pivoted at a point 10 on a device 11. The lever 9 has an arm 12 provided with adjustable weights 13 at one end, and a counter balance weight 14 at the other end. A second movable lever 15 is pivoted at a point 16 on the device 11 and carries a movable contact member 17 and the movable member 70 18^a of a bellows 18. The bellows 18 comprises, besides the movable member 18^a, a stationary member 19 having a regulating screw 20 for adjusting the time of its operation. A stationary contact terminal 21 is mounted on the device 11, and the lever 9 is operatively connected to the lever 15 by a rigid link 22 shown in Fig. 4. Referring now particularly to Fig. 3, the link 22 may be replaced by a slotted link 23 and a spring 80 24 for producing a definite time element in the operation of the relay.

Referring to Fig. 2, the rod 8 is connected to the bell crank 4 at a point 25 on the arm 4^b. The lever 9 does not require a counter balance in the vertical position, as here shown, and the arm 12 is moved to a position that is substantially at right angles to the lever 9; except for these differences, the structure is identical with that of the relay 90 shown in Fig. 1.

When the winding 2 of the electromagnet 1 is excited a predetermined amount, it attracts and draws up the movable core 3 which transmits its motion to the bell crank lever 4. By reason of the upward motion of the arm 4^a of the bell crank lever 4, the rod 8 is operated to transmit the motion of the movable core 3 to the pivoted lever 9 of the contact device 11 and cause it to turn around the point 10, thus drawing up the link 22, as shown in Fig. 1, to actuate the lever 15 upon its pivot 16 and cause the contact member 17 to engage the contact member 21, according to predetermined time-element characteristics. As shown in Fig. 1, by the elimination of the bellows 18, the engaging of the contact members 17 and 21 would be instant-

taneous but, with the bellows connected as shown, the time of engaging will vary inversely as the current in the winding 2 of the electromagnet 1.

5. If the rigid link 22 shown in Fig. 4 is replaced by the device shown in Fig. 3, the action is slightly different from that hereinbefore explained. When the electromagnet 1 is energized, the spring 24 is placed under 10 tension and the tendency of the spring to resume its initial shape draws up the lower part 18^a of the bellows 18, which may be set for any definite time of operation, thereby producing a definite limit between the time 15 when the electromagnet 1 is energized and the time when the contact members 17 and 21 engage. The usual practice is to mount the high-tension electromagnet on or near the ceiling and the device 11 near the floor. 20 However, if it is desirable to mount them on the back of a board or on a wall at approximately the same level, the rod 9 is attached to the point 25 on the bell crank lever 4, thus transmitting the motion of the plunger 3 in 25 approximately a horizontal direction to the contact device 11, as shown in Fig. 2.

Changes may be made in the size, shape and arrangement of parts without departing from the scope of our invention as set 30 forth in the appended claims.

We claim as our invention:

1. In a relay, the combination with an electromagnet and an operating rod, of a device comprising a main pivoted arm operatively connected to the operating arm, an auxiliary pivoted arm having a contact member thereon, and means for operatively connecting the said main and auxiliary pivoted arms. 35
2. In a relay, the combination with an electromagnet and an operating rod, of a device comprising a main pivoted arm operatively connected to the operating arm, an auxiliary pivoted arm having a contact 40 member thereon, and means for operatively connecting the said main and auxiliary pivoted arms.

member thereon, means operatively connected to the main arm for adjusting the device to operate at different current values and means for operatively connecting the said main and auxiliary pivoted arms. 45

3. In a relay, the combination with an electromagnet and an operating rod, of a device comprising a main pivoted arm operatively connected to the operating arm, an auxiliary pivoted arm having a contact member thereon, means operatively connected to the main arm for adjusting the device to operate at different current values 50 and a link for operatively connecting the said main and auxiliary pivoted arms. 55

4. In a relay, the combination with an electromagnet and an operating rod, of a device comprising two pivoted lever arms, means for operatively connecting the arms together and means for opposing the operation of one of the said arms. 60

5. A relay device comprising a main pivoted lever arm, an auxiliary lever arm having a contact member mounted thereon, a stationary contact member for co-operating therewith and means for operatively connecting the main and auxiliary arms together. 70

6. A relay device comprising a main pivoted lever arm, an auxiliary lever arm having a contact member mounted thereon, a stationary contact member for co-operating therewith, means for connecting the main and auxiliary arms together and means for opposing the operation of the auxiliary arm. 75

In testimony whereof, we have hereunto 80 subscribed our names this 30th day of Oct., 1913.

BENJAMIN H. SMITH.
PAUL MACGAHAN.
